(57) **CLAIM**

I claim the ornamental design for a compact, as shown and described.

DESCRIPTION

FIG. 1 is a three-dimensional perspective view of the compact with the cover open;

FIG. 2 is a front view of the compact with the cover open;

FIG. 3 is a rear view of the compact with the cover open;

FIG. 4 is a side view of the compact with the cover open;

FIG. 5 is a top view of the compact with the cover open;

FIG. 6 is a bottom view of the compact with the cover open;

FIG. 7 is a three dimensional perspective view of the compact with the cover closed;

FIG. 8 is a front view of the compact with the cover closed;

FIG. 9 is a rear view of the compact with the cover closed;

FIG. 10 is a side view of the compact with the cover closed;

FIG. 11 is a top view of the compact with the cover closed; and,

FIG. 12 is a bottom view of the compact with the cover closed.

The broken lines are shown for illustrative purposes only and form no part of the claimed design.
